ABSTRACT

The present invention relates to a process for the disruption of biological material and to a device for this process. The device according to the invention comprises in combination a pressure vessel provided with inlet and outlet means, pressure regulating means connecting the pressure vessel with a container of a compressed gaseous medium and means for determining the pressure established in the pressure vessel.

PROCESS FOR THE DISRUPTING OF BIOLOGICAL MATERIAL

BACKGROUND OF THE INVENTION

1. Field of the Invention

The invention relates to a process of disrupting biological material and to a device for effecting such process.

2. Description of the Prior Art

It is frequently necessary to disrupt biological material, such as bacteria, algae, blood cells, chloroplasts, mitochondria and the like under controlled and reproducible conditions. In a disruption process, the cell walls are ruptured by first pressurizing the cells so that an equilibrium across the cell walls is attained, and thereafter, suddenly lowering the external pressure, resulting in the cells bursting open due to the sudden decompression and expansion of the gas. In the past, rather inconvenient devices were used for this purpose. Amongst these, there may be mentioned the French press and the Hughes press, used in many laboratories. Both devices are rather inconvenient and it is rather laborious to effect the disruption of the biological material. With the known devices it is hard to maintain a substantially constant pressure, and it is difficult to carry out the process in a reproducible manner so as to obtain comparable results in different runs. The known devices are comparatively expensive, and these can be used with air only as pressure medium.

SUMMARY OF THE PRESENT INVENTION

The present invention provides a simple and convenient device for accomplishing the foregoing.

The device according to the invention is quite inexpensive and simple. The disruption of the biological material can be effected under accurately controlled and reproducible conditions, and it can be effected under any desired gaseous atmosphere.

The process according to the invention comprises introducing the biological material into a suitable pressure vessel provided with inlet and outlet means, establishing above the material a desired gaseous atmosphere and applying a controlled predetermined pressure by connecting the pressure vessel via pressure regulating means with a high-pressure gas container containing the desired gas, and permitting the biological material to flow out of the pressure vessel through a release valve. If necessary, the process may be repeated.

BRIEF DESCRIPTION OF THE DRAWING

The invention is described by way of example only with reference to the enclosed schematical drawing, which is a schematic side view of a device according to the invention.

DESCRIPTION OF THE PREFERRED EMBODIMENT

The device according to the present invention, shown schematically in the enclosed drawing, comprises a pressure vessel (1), provided with a closure (2), an outlet valve (3), an outlet (4), an inlet conduit for the gaseous medium (5), an inlet valve (6), a pressure regulating and pressure indicating valve (7) which is connected via a conduit (8) with a high-pressure gas container (9).

For carrying out the process of disrupting biological material according to the present invention, the pressure vessel (1) is charged with the biological material, the atmosphere above the sample is flushed with the gaseous medium (if this is to be other than air), so as to establish a desired gaseous atmosphere above the biological material, the cap (2) is closed tightly while the valve (6) is in the closed position, the pressure bottle (9) is opened, the pressure is adjusted by means of the valve (7), the valve (6) is opened so as to establish in the vessel (1) the desired pressure, and subsequently the valve (3) is opened so as to gradually eject the biological material through the outlet (4).

The pressure regulating valve (7) makes it possible to establish a desired gaseous atmosphere of predetermined pres-

sure, which can be adjusted in an accurate manner. Thus, it is possible to provide an atmosphere of air, oxygen, nitrogen, argon, helium or the like.

In the following, the process according to the invention is exemplified for a number of biological systems, without being restricted thereto.

EXAMPLE 1

- 10 A sample of 20 ml of 50 percent w/v Escherichia Coli in phosphate buffer was introduced into a pressure cell and an air pressure of 1,500 p.s.i. was applied. The release was effected at a rate of 3 to 4 drops per second. After one passage, a very viscous suspension was obtained due to the liberation of DNA from the disrupted cells. After a second passage through the pressure cell, in a similar manner, a breakage of 50 percent of the cells was obtained.

In the resulting sample, a protein content of 48mg/ml and a nucleic acids content of 14 mg/ml was obtained. This was determined by optical measurements of a diluted sample.

With a French press, a disruption of 100 percent of the cells can be obtained at a pressure of 15,000 p.s.i., but the biological activity of the material is diminished by such high pressures.

EXAMPLE 2

- A breakage of 50 percent of the bacterium Rhodospirillum rubrum was obtained by passage through the device according to the invention under a pressure of 1,500 p.s.i. of nitrogen. This was effected in a manner similar to that of Example 1.

By sonication, a breakage of 100 percent was obtained; both of these being determined by the release of bacteric chlorophyll.

35 The biological activities after disruption by the device according to the invention were superior as compared with the disruption by sonication or by passage through the French press, as determined by trans-hydrogenase activity.

Also in the case of Euglena (Example 3), the activity, based on determination of phosphorylation activity, was superior in the case of disruption by the process according to the invention as compared with sonication.

EXAMPLE 3

- The pressure cell according to the invention was charged with the alga Euglena, the space above the sample was flushed with nitrogen and a pressure of 500 p.s.i. of nitrogen was established. The sample was passed twice through the cell, and after the second passage, a breakage of 75 percent, determined by direct count under the microscope, was obtained.

EXAMPLE 4

- 55 Human red blood cells (1-2-percent in saline) were almost 100 percent broken by passage through the pressure cell according to the invention under a pressure of 500 p.s.i. of air.

Comparative runs were made with other compressed gases and also under increased pressures. In the latter case, the disruption of sub-cellular structures also occurred.

60 We claim:

1. A process of disrupting biological material, which comprises introducing the biological material into a suitable pressure vessel provided with inlet and outlet means, establishing above the biological material a desired gaseous atmosphere, applying a predetermined pressure on the sample by connecting the pressure vessel with a compressed source of said gas, and gradually ejecting the biological material from the pressure vessel through a release valve.
2. A process as claimed in claim 1, wherein the applied gas is air, oxygen, nitrogen, argon or helium.
3. A process as claimed in claim 1, wherein the passage through the pressure cell is repeated.
4. A process as claimed in claim 1, wherein the biological material is provided in the form of a suspension in a suitable

suspension medium so as to obtain a liquid suspension of
desired viscosity.
